DEHYDRATOR PLUG

Milton E. Chandler, New Britain, and Scott F. Hunt, Meriden, Conn., assignors to Niles-Bement-Pond Company, West Hartford, Conn., a corporation of New Jersey

Application December 3, 1947, Serial No. 789,350

17 Claims. (Cl. 183—4.8)

1

This invention pertains to dehydrating devices for removing moisture from hermetically sealed chambers and more particularly has reference to such devices in the form of dehydrator plugs for use in inhibiting corrosion from moisture in internal combustion engines while in storage or shipment. This invention is an improvement over the plastic type of dehydrator plug disclosed in United States Patent No. 2,406,993, issued September 3, 1946.

Heretofore, dehydrator plugs for internal combustion engines have been made of transparent plastic materials, such as "Tenite" (cellulose acetate butyrate) in order that the condition of the dehydrating material in the plug, as indicated by its color, could be observed without disassembling the plug. However, plastic plugs were unsatisfactory because no plastic material of adequate transparency and strength was found to be sufficiently moisture-proof to meet the required very small permissible absorption of moisture which must not exceed 2% of the weight of the dehydrating material in the plug when exposed to an atmosphere of 100° F. temperature and 100% humidity.

Various expedients have been resorted to in an effort to devise a dehydrator plug more satisfactory than those made of plastics, the most successful embodying the use of a combination glass and metal plug, in which the main body of the plug is composed of a metal die casting and the outer end a hollow glass cap through which the color of the dehydrating material can be seen. While this form of plug is an improvement over the plastic plug, it is attended with certain practical difficulties and disadvantages, the most serious of which is the difficulty and uncertainty of obtaining a moisture-tight joint between the glass cap and the metal body of the plug. Attempts to form a satisfactory joint by casting the metal of the body around the lower flanged end of the cap invariably resulted in cracking or breaking the cap from heat and pressure and were unsuccessful. Crimping a thin edge of the die-cast body over the flanged end of the glass cap also proved more or less unsatisfactory, since it failed to produce a permanent moisture-tight joint, even with the use of a rubber gasket, for the reason that the gasket tended to take a permanent set and the die-cast crimped edge did not have sufficient resiliency to hold the abutting members in moisture-tight contact.

In addition to the foregoing, it has been found to be exceedingly difficult to prevent a small amount of porosity in a certain percentage of die-

5 cast plug bodies, which porosity is sufficient to permit excessive permeation of moisture into the interior of the plug from outside atmosphere and thus rapidly reduce the dehydrating material in the plug to a condition of ineffectiveness.

10 It is accordingly an object of this invention to overcome the defects and disadvantages of prior art devices and provide a dehydrator plug which fully meets all moisture resistance requirements and which is more economical to manufacture and easy to charge and install in an engine being prepared for storage or transportation.

15 Another object resides in the provision of an improved dehydrator plug which may be kept in storage for a prolonged period without appreciable deterioration and which can be rendered operative for installation in an engine by a simple removal of a sealing cap from the end of the plug.

20 A still further object resides in the provision of improved dehydrating materials which are more economical in cost and more efficient in use.

25 With these and other objects in view, which may be incident to our improvements, our invention consists in the combination and arrangement of elements hereinafter described and illustrated in the accompanying drawing in which there is shown a suitable embodiment for the purpose of disclosing the invention. The drawing, however, is for purposes of illustration only, and is not to be taken as limiting the invention, as it will be apparent to those skilled in the art that various changes in the illustrated constructions may be resorted to without in any way exceeding the scope of the invention.

30 In the drawing:

35 Figure 1 is a partly sectional and partly side elevational view of a dehydrator plug constructed according to the invention and showing the manner in which the spark plug cable of the engine is attached.

40 Fig. 2 is a bottom plan view of the plug illustrated in Fig. 1.

45 Referring to the drawing in detail, the reference numeral 1 indicates the body of the plug which is formed of non-corrosive sheet metal in the specific novel manner hereinafter described. By the use of sheet metal instead of a die casting to form the body of the dehydrator plug, we secure several material advantages. Sheet metal, being of dense uniform texture, is free of small pores which are inherent in die castings and thus prevents leakage of moisture through 50 porosity of the metal. Also the sheet metal body

is less expensive to fabricate and lighter in weight than a corresponding die casting which reduces the cost of manufacture and transportation of the dehydrator plug.

The upper portion of the plug consists of a transparent glass cap 2, having a central cavity 3 for the reception of a portion 4 of the dehydrating material, and an outwardly extending integral flange 5 on which is seated a resilient gasket 6 of rubber or similar material. This gasket is tightly embraced by a flange 7, forming the upper end of the body member 1, which is crimped over gasket 6 after cap 2 is assembled to the body 1, as clearly shown in the drawing. The upper end of cap 2 is formed in the shape of a knob 8 with a reduced neck portion 9 and an undercut bead 10 adapted to engage a similar bead 11 on the lower end of a resilient sleeve 12 which is provided with threads 13 for the engagement of a sleeve nut on the end of the spark plug terminal (not shown). The sleeve 12 is shown in dotted lines in the drawing as it forms no part of this invention and is included in the drawing merely to illustrate one way in which the spark plug cable may be attached to our improved dehydrator plug. It is obvious that other means may be employed to attach the terminal of the spark plug cable to the end of the dehydrator plug.

The metal wall of body 1 just below flange 7 is folded in to form a flange seat 14 for the lower edge of cap 2 and gasket 6, so that when flange 7 is crimped over gasket 6 it holds the said gasket and cap firmly against seat 14, thus forming a moisture-tight joint between cap 2 and body 1. Moreover, since the sheet metal composing body 1 has considerable resiliency, it embraces gasket 6 with a resilient grip which if, after a time, the gasket tends to take a permanent set, it will still be pressed firmly against flange 5 of cap 2 and seat 14 of body 1 so as to continue to maintain a moisture-tight joint therebetween. By this novel means we have overcome one of the most important defects of prior art devices wherein it was sought to attach a glass cap to a (die-cast) metal body with a permanent moisture-tight joint, but without success, because of the unyielding nature of the metal in the die-cast body.

It will be noted that the lower outer edge of flange 5 is chamfered to form a beveled edge 15 so that the lower end of cap 2 actually contacts seat 14 of body 1 in a single line, instead of an annular area of material width. In this way, the majority of the force holding cap 2 against body 1 is exerted through gasket 6. Also the line of contact between cap 2 and seat 14 is near the inner edge of said seat and since this seat is formed from the resilient metal of body 1, it tends to yield to any localized pressure from the lower end of cap 2, so that if a bending force or accidental blow is applied to cap 2, the resulting stress is absorbed by gasket 6 and resilient seat 14, thus preventing spalling of the lower outer edge of cap 2 or breaking of the cap.

Near its lower end, body 1 is pressed in to form an annular inwardly-projecting rib 16 which serves as a seat for circular discs 17 of filter paper and wire mesh screen 18. After assembling against rib 16, discs 17 and 18 are held securely in position by crimping the bottom edge of body 1 to form an inwardly projecting flange 19, as clearly shown in Fig. 1.

The upper portion of body 1, below flange 14, is pressed into a polygonal shape so as to provide a plurality of flat surfaces 20 for the application of a wrench. Below its polygonal portion, body 1

is pressed in to form a shoulder 21 which serves as a seat for a gasket 22, below which body 1 is provided with a threaded portion 23 for engagement with a similar threaded portion 24 of a sheet metal sealing cap 25. When cap 25 is threaded into body 1 so that its flared upper edge 26 firmly engages gasket 22, a moisture-tight joint is formed between cap 25 and body 1. Sealing cap 25 is applied to body 1 during storage and transit of the dehydrator plug and is removed just before the plug is applied to an engine cylinder.

For dehydration purposes, we have found that silica gel is by far the most suitable material, as it never becomes progressively moist in a humid atmosphere and the moisture which it adsorbs from the surrounding atmosphere can only be driven off by the application of heat to a degree far above that ever attained by nature. Silica gel may be treated with certain salts, such as an iodine or cobalt salt, which gives it a distinctive color, such as deep blue, when dry, and which color gradually changes to another distinctive color, such as pale pink, when saturated with moisture. A visual indication is thus afforded of the state of saturation of the silica gel so that it can be replaced with fresh, dry material before it is completely saturated. The use of silica gel thus chemically treated for dehydration purposes is old in the art and we do not claim its use except in combination with other novel features of this invention. However, we have found that when silica gel is treated as indicated it loses some of its moisture adsorptive power and is, moreover, more expensive than untreated silica gel. We have therefore devised the following novel and improved means of using silica gel as a dehydration material in this invention. In the glass cap portion of our dehydrator plug we place chemically treated silica gel 4 containing a moisture-control indicator which can be readily observed through the transparent wall of the cap, while the main body of the plug is filled with untreated silica gel 27, which is more moisture adsorbent and less expensive than the treated silica gel. By this arrangement we have found that the color of the treated gel in the glass cap is a satisfactory indication of the moisture-content condition of both the treated and untreated gel. We thus increase the moisture adsorbent capacity and reduce the cost of the whole silica gel content of the dehydrator plug by using only a minor portion of treated gel.

Substances of the silica gel type have the disadvantage that, being extremely hard, dust formed through attrition may damage the parts which the dehydrator plug is intended to protect. Therefore, in order to prevent the escape of such dust from the dehydrator plug, the filter paper 17 and wire mesh screen 18 are provided to close the bottom of plug against the passage of solid particles while affording free passage to moisture and water vapor.

While a suitable mechanical arrangement of the invention has been hereinabove described and illustrated, it is to be understood that the invention is not to be limited to the particular form so-disclosed, but such changes in the size, shape and arrangement of the various parts and of the materials thereof may be resorted to without departing from the spirit of this invention or exceeding the scope of the appended claims.

What we claim as now and desire to secure by Letters Patent is as follows:

1. A dehydrating device comprising dehydrat-

ing material contained in a seamless resilient metal tubular body connected to a substantially hollow, transparent, moisture-impervious cap hermetically and yieldably sealed to one end of said body by deforming said end of said body over a yieldable gasket surrounding the connecting end of said cap.

2. A device as set forth in claim 1 having a resilient, permanently moisture-tight joint between said body and cap which permits limited relative movement of said body and cap.

3. A device as set forth in claim 2, in which said body and cap each provide a substantial chamber for dehydrating material.

4. A device as set forth in claim 3, in which said body is formed of a single, unitary piece of non-corrosive sheet metal without joints or seams.

5. A device as set forth in claim 4, in which said cap is formed of a single, unitary piece of glass.

6. A device as set forth in claim 1 having a dust-imperforate but moisture-perforate closure for the end of said body opposite said cap.

7. A dehydrating device comprising a hollow, opaque body and a hollow, transparent cap each of which form a substantial chamber for dehydrating materials, dehydrating material in said body which does not change its color with adsorption of moisture, and dehydrating material in said cap which changes its color with adsorption of moisture, whereby the deterioration of said dehydrating material upon absorption of moisture can be observed through the walls of said cap.

8. A device according to claim 7, in which the color-changing portion is a minor fraction of the total dehydrating material but sufficient to indicate the moisture content of all the dehydrating material in said chamber.

9. A device for dehydrating the air in an engine cylinder comprising dehydrating material in a seamless resilient metal, tubular body connected to a substantially hollow, transparent, moisture-impervious cap hermetically and yieldably sealed to one end of said body by deforming said end of said body over a yieldable gasket surrounding the connecting end of said cap, means connecting said body to said cylinder and means on said cap for connecting an ignition cable terminal.

10. A device according to claim 9 having a re-

silient, permanently moisture-tight joint between said body and cap.

11. A device according to claim 9, in which said body is formed of a single, unitary piece of non-corrosive, seamless sheet metal.

12. A device according to claim 9, in which said cap is made of a single, unitary piece of glass.

13. In a device as set forth in claim 9, a unitary, tubular body formed by drawing and stamping a flat piece of seamless resilient sheet metal.

14. A device for dehydrating the air in an engine cylinder and for supporting an ignition cable terminal comprising a seamless resilient metal tubular body connected to a substantially hollow, transparent glass cap hermetically sealed to one end of said body by deforming said end of said body over a yieldable gasket surrounding the connecting end of said cap, and a dust-imperforate but moisture-perforate closure for the other end of said body.

15. A device according to claim 14, in which said body and cap are filled with dehydrating material.

16. A device according to claim 14, in which said body is adapted for insertion in a spark plug aperture in said cylinder.

17. A device according to claim 14, in which said body is provided with screw threads adapted to engage the threads in a spark plug hole in said cylinder and hold said device in moisture-tight engagement in said cylinder.
